UNITED STATES PATENT OFFICE.

HARVEY A. BERNHARDT, OF CHICAGO, ILLINOIS, ASSIGNOR TO BERNHARDT INCORPORATED, OF CHICAGO, ILLINOIS.

DESIGN FOR A PORTABLE SAND JAR.

Application filed October 15, 1928. Serial No. 28,490. Term of patent 7 years.

To all whom it may concern:

Be it known that I, HARVEY A. BERNHARDT, a citizen of the United States, residing at Chicago, in the county of Cook and State of Illinois, have invented a new, original, and ornamental Design for Portable Sand Jars, of which the following is a specification, reference being had to the accompanying drawing, forming a part thereof.

The figure shown represents a side elevation view of the article showing my new design.

I claim:

The ornamental design for a portable sand jar as shown.

HARVEY A. BERNHARDT.
